CLAIM

The ornamental design for the teeth shape of a socket, as shown and described.

DESCRIPTION

FIG. 1 is a perspective view of my new design for the teeth shape of a socket;

FIG. 2 is a top view thereof;

FIG. 3 is a partial sectional front view thereof;

FIG. 4 is a bottom view thereof; and,

FIG. 5 is a top view thereof, the bolt shown in broken lines therein forms no part of my claimed design and illustrates environment only.

Broken lines are included for the purpose of illustrating environment and forms no part of the claimed design.
